Primary Examiner—Ted Shooman*Assistant Examiner*—Mitchell I. Siegel*Attorney, Agent, or Firm*—James D. Christoff**[57] CLAIM**

The ornamental design for a blade-type golf putter head, as shown and described.

DESCRIPTION

FIG. 1 is a top, rear, right side perspective view of a blade-type golf putter head showing my new design;

FIG. 2 is a bottom and right side view thereof;

FIG. 3 is a front elevational view thereof;

FIG. 4 is a left side elevational view thereof, the right side being a mirror image;

FIG. 5 is a top plan view thereof;

FIG. 6 is a rear elevational view thereof; and,

FIG. 7 is a bottom plan view thereof.

The broken line drawing of a golf club shaft is for illustrative purposes only and forms no part of the claimed design.
